UNITED STATES PATENT OFFICE.

LOUIS NAGLEE BRUNER, OF ZURICH, SWITZERLAND.

MACHINE FOR GRINDING OR TRUING BOTTLE-STOPPERS AND OTHER ARTICLES.

1,301,377.

Specification of Letters Patent.

Patented Apr. 22, 1919.

Application filed November 13, 1916. Serial No. 131,163.

To all whom it may concern:

Be it known that I, LOUIS NAGLEE BRUNER, a citizen of the United States of America, residing at 7 Bellerivestrasse, Zurich, Switzerland, glass manufacturer, have invented certain new and useful Improvements in or Relating to Machines for Grinding or Truing Bottle-Stoppers and other Articles, of which the following is a specification.

10 This invention has reference to machines for grinding or truing bottles, stoppers or other articles.

The invention is however applicable to any grinding machines in which the grinding wheels or abrading devices are carried by slides which are automatically moved up toward the work by cams or otherwise, and in which the exact adjustment of the grinding wheel relatively to the work is effected 20 by an adjusting wheel usually operated by hand.

In certain known machines of this kind an adjusting device has been proposed comprising an annularly grooved hub which 25 works on a threaded stud fixed in the slide carrying the grinding wheel. In the groove of the hub a forked operating lever engages for the purpose of moving the slide toward and from the work, and the hub carries a 30 hand-wheel for the purpose of effecting the necessary adjustments manually.

Such adjustments were only intended to be made at intervals and were not adapted to compensate for the extremely minute degree of wear occurring at each individual 35 grinding operation.

Now according to this invention improved means are provided for giving, automatically, a very fine or micrometer adjustment 40 of the grinding wheel forward toward the work after each individual grinding action, such adjustment being so fine in fact that it amounts to only a minute fraction of a millimeter at each operation. This micrometer 45 adjustment is effected by means of link-work which in the to-and-fro motion of the slide serves to actuate the operative parts of a suitable feed device. By reason of the link-work actuation, the arrangement is distinguished 50 from known means in which the adjustment is effected by tappets actuated by impact only, and therefore liable to be irregular where very fine adjustments are concerned.

55 In applying the invention, by way of example to a machine of the kind referred to,

the grooved hub carrying the hand wheel, is combined with a bracket for carrying the main portion of the improved feed device. This bracket has a boss or eye at the top 60 which fits over part of the nave of the hand wheel and which at the bottom is suitably guided so that it can move freely parallel with the threaded stud. The said bracket is combined with a radius arm for actuating 65 the pawl arrangement of the feed device positively, as hereinafter explained.

In order that the invention may be clearly understood and readily carried into effect reference will now be had to the accompanying 70 diagrammatic drawings in which:—

Figure 1, is a general side view of one example of the improved feed mechanism, the parts being in the position in which the grinding tool is in contact with the work. 75

Fig. 2 is a vertical part section on the line 2—2 and 2¹—2¹ of Figure 1.

Fig. 3, is a horizontal part section through the aforesaid bracket on the line 3—3 of Fig. 2. 80

Fig. 4 is a detail view taken longitudinally through the hub.

Fig. 5 is a side view of the operating lever and cam.

In these drawings, *a* is the annular groove 85 in hub, which is provided with the hand wheel *a*¹, *b* is the threaded stud on which it works after the manner of a nut, *c* is the slide (carrying the grinding wheel) in which the stud *b* is secured, and *d* is a forked lever 90 engaging the hub *a* and serving to move the slide relatively to the work to press the grinder on to the latter at the proper times, this lever being mounted on a stand *d*¹ (see Fig. 5) and carrying a roller *d*² which is 95 acted on by a cam *d*³ carried by a shaft *d*⁴ as in known arrangement.

e is the aforesaid bracket which serves to carry the improved feed device. *f* is the boss or eye thereof fitting over a sleeve *a*⁵ 100 one end of which is secured to the nave of the wheel *a*¹.

The said wheel *a*¹ is in this case provided around its edge with notches or recesses *a*² forming worm-teeth. 105

g *g* are guide pieces projecting from the bottom of the bracket. These guides lie on each side of the actuating or presser lever *d*, after the manner of a clip or fork, so that the bracket can move along the stud *b* but 110 will not turn with the wheel *a*¹.

One side of the aforesaid hub groove is

formed by the right-hand edge f^1 of the boss f and the other by a flange a^3 on the sleeve a^x .

In the bottom or hanging part of the bracket e is mounted a worm h which meshes 5 with the teeth a^2 formed in the periphery of the hand-wheel or its equivalent a^1 mounted on the annularly grooved hub or nut a . The stem or spindle h^1 of this worm is fitted in 10 two bosses e^1 . It carries a ratchet disk or wheel i operated by a spring pawl j^1 at the end of a rocking lever or radius arm j mounted coaxially with such ratchet wheel and forming part of a link work system. In 15 this way the pawl is constantly connected with the parts which operate it, and an even and regular action is assured.

The bracket e and the parts carried thereby, being mounted on the aforesaid threaded-stud b will move to-and-fro along with 20 the slide which carries the grinding wheel. In order therefore to cause the pawl or clawker j^1 to operate the ratchet wheel during these to-and-fro movements, the rocking lever or radius arm j , (which may be normally more or less inclined to the horizontal) is connected to one end of a link k which is more or less at right angles thereto. The other end of this link is mounted on a stationary pivot pin k^1 adjustably secured in a 25 slotted bar l screwed into the main frame of the machine.

The arrangement is such that as the bracket moves to-and-fro with the slide, the link is caused to rock on its stationary pivot 30 and imparts a corresponding rocking motion to the pawl. The movements of this latter therefore turn the ratchet disk i through the space of one or more teeth, and cause it, by means of the aforesaid worm, to 35 give a very minute rotary movement to the hand-wheel a^1 with which it is geared, and therefore also to the annularly grooved hub or nut a of said wheel, thus feeding the slide and the grinding wheel forward relatively 40

to the lever d and in the direction of the 45 work, at each operation, by the requisite imperceptible amount necessary to compensate for the slight wear on the edge of the wheel.

The extent of such movements can be 50 varied by adjusting the throw of the pawl or clawker, for instance by moving the adjustable pivot or the link above mentioned, in the slotted bar which carries it.

In the full line position (on the left) it is 55 given the smallest feed, while at the right-hand extremity of the slot it gives the largest feed.

The above arrangement is described only 60 by way of example, as it will be obvious that the invention may be modified in various ways in carrying the same into practice without departing from the general nature thereof.

I claim:—

1. In a grinding or truing machine of the kind referred to, the combination of a slide carrying the grinder, a threaded stud connected with said slide, a grooved hub on said stud, a worm and worm gear for partly rotating such hub at each stroke, and a presser lever engaging in said grooved hub, substantially as described.

2. In a grinding machine of the kind referred to, the combination of a reciprocating 75 slide, an adjusting screw fixed to said slide, an adjusting wheel having a nut-like hub on said screw, and link work for slightly rotating such adjusting wheel at each to and fro motion of the slide, substantially as described.

In testimony whereof I have signed my name to this specification.

LOUIS NAGLEE BRUNER.
